UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING LOOM.

1,360,586.

Specification of Letters Patent. Patented Nov. 30, 1920.

Application filed January 2, 1919. Serial No. 269,199.

To all whom it may concern:

Be it known that I, EPPA H. RYON, a citizen of the United States, residing at Waltham, in the county of Middlesex and State 5 of Massachusetts, have invented a new and useful Weft-Replenishing Loom, of which the following is a specification.

This invention relates particularly to a 10 weft replenishing loom of the type having a movable weft carrier magazine in which the weft carriers are preferably arranged in groups and in which mechanism is provided for advancing successive groups of weft carriers to operative position.

15 This general type of weft replenishing mechanism is shown in my prior Patents Nos. 939,326; 951,659; 1,032,709 and 1,045,443. Such mechanism is commonly used on drop box looms using a plurality of shuttles, 20 and a particular weft carrier in the operatively positioned group is moved to transfer position whenever the corresponding shuttle becomes active. The magazine is advanced to bring another group to operative position 25 whenever any weft carrier in a group or a particular weft carrier in a group is transferred.

It is the object of my present invention to 30 provide improved actuating devices for the transfer and feeding mechanism by means of which the several operations may be performed in a reliable and accurate manner.

With this general object in view, an important feature of my invention relates to the 35 provision of a single actuating cam and a single lever moved thereby, together with connections through which said lever controls both the transfer and the feeding operations.

40 Another feature relates to the provision of a storage spring for advancing the magazine whenever the spring is tensioned and released by the control mechanism.

45 My invention further relates to arrangements and combinations of parts hereinafter described and more particularly pointed out in the appended claims.

A preferred form of my invention is shown 50 in the drawings, in which—

Fig. 1 is a side elevation of my improved operating mechanism;

Fig. 2 is a similar view of certain parts taken in a different position, and

Fig. 3 is a front elevation of the parts shown in Fig. 1.

Referring to the drawings, I have shown 55 a portion of a loom side 10 and a breast beam 11 (Fig. 3) upon which is mounted a rotary magazine 12 having a transerrer 13 to which is connected the weft carrier 60 engaging member 14. The transerrer 13 is pivoted at 15 to the magazine frame. A depending hook 16 is pivoted at 17 to the transerrer 13 and is under the control of a weft detecting member or feeler 18 projecting rearwardly to intermittently engage the 65 active weft carrier. When the hook 16 is operatively located, as shown in Fig. 1, it is positioned for engagement by the head 19 of a plunger 20 slidable vertically in a fixed 70 bearing 21. The plunger 20 is connected by a rod 22 to an actuating lever 23 pivoted at 24 to a bracket 25 fixed to the loom side 10.

All of the parts thus far described are or 75 may be of the usual construction, as fully shown in my prior Patent No. 1,032,709.

The lever 23 is provided with a cam roll 26 (Fig. 1) positioned in the cam groove 27 of a side cam 28 mounted on the usual 80 bottom or cam shaft 29. This cam makes one revolution to every two picks of the loom, and the lever 23 is regularly oscillated thereby, giving the head 19 of the plunger 20 a downward operative movement at 85 every alternate beat of the lay and actuating the transerrer whenever the feeler 18 permits the hook 16 to be engaged by the head 19.

The mechanism for advancing the magazine 90 from group to group is substantially the same as that shown in my prior Patent, No. 1,045,443, comprising a worm wheel associated with the magazine, and a worm engaging therewith and movable longitudinally as well as angularly. The worm and 95 worm wheel are not shown in the drawings, but are clearly described in my prior patent, and it is sufficient for the purposes of this invention to state that the worm is fixed to a vertical shaft 30, the lower end of 100 which is squared and slidable longitudinally through a beveled pinion 31 (Fig. 3) driven by a beveled gear 32 loosely mounted on a stud 33 carried by a bracket 34 fixed to the loom side 10. A disk 35 (Fig. 2) is secured 105

to the beveled gear 32 and is provided with a series of notches 36 on its periphery and a series of notches 37 on its outer side surface.

5 A member 38 is pivoted to move freely about the axis of the stud 33 and is provided with two arms 39 and 40. The arm 39 is provided with a spring plunger 41 adapted to engage one of the notches 37 in 10 the disk 35, while the arm 40 constitutes a striker adapted to engage and lift a locking latch 42 normally seated in one of the notches 36. The latch 42 is mounted upon a fixed pivot 43 upon which is also mounted 15 a second or hold-back latch 44 adapted to engage another one of the notches 36 and to prevent backward movement of the plate as the latch 42 is raised. A coil spring 45 positioned between portions of the latches 20 42 and 44 yieldingly forces each of the latches into engagement with the notches 36.

A vertically movable bar 46 is pivoted at 25 47 to the arm 39 of the member 38 and is provided with a lug 48 which is at times engaged by an offset lug 49 formed on the end of the lever 23. Normally, however, the lugs are out of engagement, as is shown in Fig. 1. A rod or link 50 is pivoted at its upper end to the transerrer 13 and at its 30 lower end extends through an opening in the upper end of the bar 46. A spring 51 is positioned between the headed lower end of the rod 50 and the offset upper end of the bar 46. The lever 23 is further provided with an upward extension 52 and an 35 adjusting screw 53 adapted to engage the bar 46 as the lever 23 is swung upward. A heavy coil spring 54 encircles the stud 33 and is connected at one end to a collar 40 55 fixed to said stud and at the other end to the angularly movable member 38.

Having described the details of construction of my improved actuating mechanism, I will now describe its operation. The plunger 20 and head 19 are reciprocated vertically at every alternate beat of the lay, and upon weft exhaustion the hook 16 is positioned for engagement by the head 19. The transerrer is thus actuated to insert a fresh 45 weft carrier and through the rod 50 the transerrer moves the bar 46 to bring its lug 48 into the path of the lug 49 on the lever 23, as shown in Fig. 2. As the lever 23 moves upwardly, the member 38 is moved about the axis of the stud 33 and against the tension of the spring 54. Such movement of the member 38 permits the spring plunger 39 to engage the next notch 37 in 50 the disk 35 and also causes the arm 40 to disengage the locking latch 42 from the notch 36. As this disengagement occurs, the stop screw 53 in the upward extension 55 of the lever 23 engages the bar 46 and forces it rearwardly until the lugs 48 and 60 49 are disengaged. The member 38 then

makes a partial revolution under the influence of the spring 54, advancing the disk 35 and beveled gear 32, and thus feeding the magazine through the beveled pinion 31 and parts associated therewith.

As the disk 35 revolves, the latch 42 engages the next notch 36 and the feeding mechanism comes to rest in its original position, but with the next group in the magazine advanced to operative position.

It will thus appear that the transfer and feeding operations are entirely controlled by the single lever 23 and cam 28, and furthermore that the magazine feed itself is spring-actuated. These magazines are of considerable weight, and by this construction it is unnecessary for the magazine to make sudden or rapid movements.

Having thus described my invention, it is evident that changes and modifications can be made therein by those skilled in the art without departing from the spirit and scope thereof as set forth in the claims, and I do not wish to be otherwise limited to the details herein disclosed, but what I claim is:—

1. In a weft replenishing loom, a weft carrier magazine, feeding means to advance a fresh weft carrier in said magazine to transfer position, transfer mechanism, a single continuously moving cam, and connections through which said cam controls the movements of both said transfer mechanism and said feeding means.

2. In a weft replenishing loom, a weft carrier magazine, a transerrer, feeding means to advance a fresh weft carrier in said magazine to transfer position, and continuously actuated cam mechanism effective to actuate said transerrer directly and said feeding means indirectly.

3. In a weft replenishing loom, a weft carrier magazine, a transerrer, feeding means for said magazine, an actuating member, operative connections from said member to said transerrer, a spring to actuate said feeding means, and additional connections from said member to said feeding means effective to tension said spring during the inoperative movement of said transerrer and before each feeding operation.

4. In a weft replenishing loom, a weft carrier magazine, a transerrer, feeding means to advance a fresh weft carrier in said magazine to transfer position, a spring to actuate said feeding means, and an actuator effective when moved in one direction to operate said transerrer, and when moved in the opposite direction to tension said spring.

5. In a weft replenishing loom, a weft carrier magazine, a transerrer, feeding means to advance a fresh weft carrier in said magazine to transfer position, a spring to actuate said feeding means, an actuator effective when moved in one direction to operate said transerrer and when moved in

the opposite direction to tension said spring, and a connection between said actuator and said feeding means rendered operable by movement of said transferrer.

5 6. In a weft replenishing loom, a weft carrier magazine, a transferrer, feeding means to advance a fresh weft carrier in said magazine to transfer position, a spring to actuate said feeding means, an actuator effective 10 when moved in one direction to operate said transferrer and when moved in the opposite direction to tension said spring, and a connection between said actuator and said feeding means rendered operable by movement 15 of said transferrer and rendered inoperable by continued movement of said actuator.

7. In a weft replenishing loom, a weft carrier magazine, a transferrer, feeding means to advance a fresh weft carrier in said magazine to transfer position, an actuator, means 20 to move said actuator on every alternate pick of the loom, a weft feeler, feeler-controlled connections between said actuator and said transferrer, and transferrer-controlled 25 connections between said actuator and said feeding means.

8. In a weft replenishing loom, a weft carrier magazine, a transferrer, and feeding means to advance a fresh weft carrier in said 30 magazine to transfer position, said means including a feed pawl, a spring to give said pawl a feeding movement, and an actuator effective first to give said transferrer an operative movement and on the return movement 35 of said transferrer to tension said spring and finally to release said pawl.

9. In a weft replenishing loom, a weft carrier magazine, a transferrer, feeding means to advance a fresh weft carrier in said magazine to transfer position, a cam, a lever 40 moved thereby alternately in opposite directions, a weft feeler, feeler-controlled connections between said lever and said transferrer, and connections between said lever and said feeding means, whereby movement of said 45 lever in one direction actuates said transferrer and movement in the opposite direction controls the magazine feed.

10. In a weft replenishing loom, a weft carrier magazine, feeding means to advance 50 a fresh weft carrier in said magazine to transfer position, an actuating lever, a bar connecting said lever to said feeding means, and a device on said lever effective to disconnect said bar from said lever at a predetermined point in the travel of said lever.

11. In a weft replenishing loom, a weft carrier magazine adapted to receive weft carriers in groups, feeding means to advance said magazine to bring successive groups 60 into operative position, positioning devices effective to place a selected weft carrier in the operative group in position for transfer, a transferrer, a cam-actuated member, operative connections from said member to said 65 transferrer, and mechanism controlled by said member effective to actuate said feeding means.

In testimony whereof I have hereunto affixed my signature.

EPPA H. RYON.
